L. W. SCHALLER

DAMPER FOR FIREPLACES

Filed June 6, 1925

UNITED STATES PATENT OFFICE.

LOUIS W. SCHALLER, OF PORTLAND, OREGON.

DAMPER FOR FIREPLACES.

Application filed June 6, 1925. Serial No. 35,291.

To all whom it may concern:

Be it known that I, LOUIS W. SCHALLER, a citizen of the United States, residing at Portland, in the county of Multnomah and State of Oregon, have invented a new and useful Damper for Fireplaces, of which the following is a specification.

My invention relates to dampers for fireplaces in which a horizontal metal frame is built into the brick work of the flue, and in which a cover is resting loosely on the frame.

The objects of my invention are to provide a construction which avoids the pivots between frame and cover; which has the cover resting on the top of the frame and therefore yields a more air tight joint.

Other objects are to make provisions for air insulation whereby the supporting bar for the brick work will not be affected by a warping of that portion of the frame which is directly exposed to the heat.

Other objects and advantages are to be found in the construction and arrangement of parts, as will be described in the specification, and particularly pointed out in the appended claims.

I attain these objects with the device illustrated in the accompanying drawing, in which—

Fig. I is a plan view of the entire device.
Fig. II is an elevation of the front edge of Fig. I.

Fig. III illustrates the configuration of the pivoted edge of the cover where the same rests on the frame.

Fig. IV shows a fireplace in section with my invention in place.

Similar numerals refer to similar parts throughout the several views.

The frame consists of a horizontal base, the two side members 1 and the rear member 2 of which are masoned into the brick work 3. The vertical walls, cast integrally with the base, surround the flue opening. The upper edges of the two side walls 4 and the rear wall 5 slope down toward the front wall 6 and support the cover 7. The front wall 6 is somewhat higher than the lowest point of the abutting side walls 4 and thus prevents a sliding of the cover 7. Besides a suitable reinforcing rib 9 on top of the cover 7, the underside of said cover, where it rests at the lowest point of the side walls 4, is reinforced with two short half-

round ribs 10 which rest in corresponding semi-circular notches 8 in said side walls. This half-round rib takes the place of the pivot which in constructions of this kind usually extends from the cover into a hole in the side wall. A nose 11 on the half-round rib 10 prevents the cover from sliding toward either side. Cast integrally with the vertical front wall 6 and the corresponding base member are three or more ears 12, the upper edges of which are level with the upper edge of the vertical front wall 6. The so-called supporting bar 13 rests on the ears 12 and the upper edge of the vertical front wall 6 and has downwardly extending ears 14 which are fastened to the ears 12 of the frame by means of bolts 15. A rearwardly extending projection 16 at the rear edge of the supporting bar 13 prevents the cover 7 from being swung to an extent where closing by gravitation would fail to take place. The supporting bar 13 furnishes a bench for the superimposed front brick wall 17 and though the base at this point may be warped by the heat of the fire, the intervening air space will keep the supporting bar 13 cool and straight and prevent cracks in said brick wall 17. The cover can be lifted by means of a chain 18 which is attached near the rear edge of the cover and which extends thence through the front brick wall.

Having thus described my invention, it will be seen that my objects have been accomplished and, though I have shown the preferred form of construction, I reserve to myself the right to make minor changes, providing I do not contravene the spirit and principle of my invention.

I claim:

1. In a device of the character described, the combination of a frame comprising horizontal base members, and vertical walls at the inner edge of said base members, the vertical side walls and the rear wall sloping downwardly toward the front wall, a vertical front wall rising above the lowest point of the abutting side walls, ears cast integrally with the vertical front wall and the corresponding base member and extending upwardly to a level with the upper edge of the vertical front wall, a supporting bar resting on the upper edge of said ears and being attached thereto, with a cover

resting freely on top of the side and rear walls and resting with the two front corners at the lowest point of the side walls.

2. In a device of the character described, the combination of a flat, horizontal frame, upwardly extending walls at the inner edge of the horizontal frame, the edges of the rear and side walls sloping downwardly from the rear toward the front, a front wall 10 extending above the lowest point of the side walls, a semicircular notch traversing each side wall at its lowest point, a plurality of upwardly extending ears cast integrally with the frame and the front wall and at 15 right angles thereto, the upper edge of said ears being level with the upper edge of the front wall, a supporting bar resting on the

upper edges of the ears and the front walls, downwardly extending ears from the supporting bar bolted to the sides of the upwardly extending ears, a rearwardly extending projection from the rear edge of the supporting bar, and a flat cover resting freely on the top edges of the side walls and the rear wall, said cover having a reinforcing rib on the upper surface along the longitudinal center line, a half-round rib resting in the semicircular notch of the side wall, and a ridge across the half-round rib at the inner side of the side wall. 20 25 30

Signed by me at Portland, Oregon, this 1st day of June, 1925.

LOUIS W. SCHALLER.
